United States Patent Office

Des. 230,460

Patented Feb. 26, 1974

230,460

FRY PAN

Gerald Gulotta, New City, N.Y., assignor to J. C.
Penney Company, Inc., New York, N.Y.

Filed Apr. 26, 1972, Ser. No. 247,923

Term of patent 14 years

U.S. Cl. D7—02

FIG. 1

FIG. 2

FIG. 5

FIG. 4

FIG. 1 is a top plan view of a fry pan showing my new design;

FIG. 2 is a side elevation view thereof;

FIG. 3 is a bottom plan view thereof;

FIG. 4 is a front end view thereof; and

FIG. 5 is a rear end view thereof.

I claim:

The ornamental design for a fry pan, substantially as shown and described.
